PANEL FOR A CABINET DOOR

Herman W. Bernard, 304 Edgedale Drive,
High Point, N.C. 27262

Filed Nov. 19, 1968, Ser. No. 14,538

Term of patent 3½ years

Int. Cl. D6—01

U.S. Cl. D33—1

FIG. 3

FIG. 2

FIG. 1

FIG. 1 is a front elevational view of a panel for a cabinet door embodying my design;

FIG. 2 is a left end elevational view of FIG. 1;

FIG. 3 is a top plan view of FIG. 1; and

FIG. 4 is a sectional view taken along line 4—4 of FIG. 1.

I claim:

The ornamental design for a panel for a cabinet door, as shown.
